WEB TENSION CONTROL MECHANISM**William F. Huck, Forest Hills, N.Y., assignor to Huck Company, New York, N.Y., a partnership****Application April 10, 1957, Serial No. 651,875****7 Claims. (Cl. 271—2.3)**

This invention relates in general to web control devices, and more particularly to devices for closely controlling the tension in continuous webs undergoing a variety of operations.

In certain arts where operations are carried out on a continuous moving web of cloth, paper or the like, it is important that the tension of the moving web be adjustable at certain points without respect to its tension at other points, and at the same time it is desirable to prevent any material change of web length between positions where the desired operations are being carried out upon the web.

It is an object of this invention to provide a web tension control device which will automatically maintain the tension of a continuous moving web substantially constant in one region within certain predetermined limits, and independent of any changes occurring in another region.

It is another object of this invention to provide a tension control device for use with a moving web of paper, cloth and the like, in which the web length between fixed positions is not materially altered by action of the web tension adjustment device.

It is another object of this invention to provide a web tension control mechanism which is simple and economical of construction and which may be used for continuous webs of cloth, paper, metal or the like.

Another object of this invention is to provide a web tension control mechanism which acts quickly and automatically to compensate for undesired changes in tension of the web, so as to maintain the web tension within certain predetermined limits.

Briefly, the invention provides a pair of web carrying roller carriages, both movable back and forth in the direction of web travel, the web being wrapped in "S" or serpentine fashion about the rollers of one carriage, and then passed about a roller of the other carriage. The first carriage, when moved by a change in the entering web tension, actuates a servomechanism to move the second carriage in the same direction. A constant tension device controlled by the first carriage preserves the desired tension on the entering web, independent of changes in tension of the departing web, because the effective amplification of the servo action isolates the first carriage from reactions due to tension effects on the second carriage. The above is accomplished without any appreciable effect on the web length distributed about the frame rollers.

The foregoing and other objects and advantages will become apparent when the following specification is read in conjunction with the attached drawings, in which:

Figure 1 is a side elevation of a web tension control device embodying this invention.

Figure 2 is a horizontal offset sectional view taken along the planes 2—2 of the device illustrated in Figure 1.

Figure 3 is an offset sectional view taken along the planes 3—3 of the device illustrated in Figure 1.

Figure 4 is a sectional view of the fluid pressure servo control mechanism utilized in the device illustrated in Figure 1.

2

Although the following describes the invention as used with a moving continuous paper web through a printing press, it is obvious that the invention may be used for maintaining proper tension in continuous web of cloth, metal, or the like in which various operations other than printing are to be performed upon the moving continuous web. Referring now to the drawings, and Figure 1 particularly, a continuous web 10 is illustrated as entering the control mechanism at the position R, in a horizontal plane.

The web tension control mechanism comprises a first or lower section and a second or upper section. The web 10 entering the mechanism at the position R enters the lower section first. The first or lower section includes a variable tension compensator which may be similar to the web tension control mechanism described and illustrated in the U.S. patent application of W. F. Huck, filed November 16, 1953, S.N. 392,292, now Patent No. 2,787,463, and includes two rollers 12 and 14 around which the web 10 is wound in a serpentine fashion, then led from roller 14 to an idler roller 16 and then directed upwardly in a substantially vertical direction to the second or upper section of the web tension control mechanism.

The rollers 12, 14 and the idler roller 16 are mounted in vertical carriage frames 18 and 20 (the latter shown in Fig. 3) which are arranged to slide freely along the horizontal bars 22 and 24 by means of sleeve bearings 26 and 28. The roller 12 is shown as driven by a drive pulley 30 acting through a V-belt 32 passing around an adjustable pulley 31 mounted upon the shaft carrying the roller 12. The vertical carriage frames 18 and 20 carrying the rollers 12, 14 and 16 and forming a compact movable carriage, are urged to the right as by an adjustable spring mechanism including a coil spring 34 connected to the carriage frame 18 at a projection 36 and to a member 38 of the machine frame by means of an eye bolt 40 passing through a projection 42 of the frame 38, and adjusted by means of a nut 44. Obviously, other equivalent means for urging carriage frames 18 and 20 to the right may be substituted; for example, an air or fluid cylinder arrangement. Moreover, so far as the instant invention is concerned, the tension controlling V-belt drive may be replaced by equivalent mechanism of other forms.

The second or upper section of the complete web tension control means will now be described. Situated above and offset to the right of the lower section support bars 22 and 24 are two parallel upper section horizontal support bars 46 and 48. A pair of vertical carriage members 50 and 52 having sleeve bearings 54 and 56, respectively, are arranged for sliding movement upon the support bars 46 and 48. An idler roller 58 is carried by the upper carriage members 50 and 52. The vertical traveling web 10 leaving the idler roller 16 on the lower section of this device is passed around the upper section idler roller 58 and thence out of the device in a horizontal plane to the position "S" as illustrated in Figure 1.

The upper section carriage member 50 is movably connected to the lower section carriage frame 18 by means of a link 60, and a fluid pressure cylinder control rod 62. A fluid pressure cylinder 64 is rigidly fastened to the carriage member 50 by means of bolts 66, and receives the control rod 62 in a manner disclosed in detail below. The cylinder 64 is provided with a piston 68 and piston rod 70. As seen in Figure 1 the piston rod 70 is clamped rigidly to the upper section support bar 46 by means of the clamping member 72, so that the piston 68 and piston rod 70 are incapable of movement relative to the support bar 46. The fluid pressure cylinder 64 and its associated control mechanism are disclosed in detail in Figure 4. The cylinder 64 is provided with a valve chamber 74 to which is

connected a conduit 76 from a source of fluid pressure; for example, compressed air. Within the valve chamber 74 is positioned one end of the cylinder control rod 62 carrying two spaced valve members 78 and 80 for covering or uncovering valve ports 82 and 84, respectively, connecting the valve chamber 74 with the interior of the cylinder 64. The valve ports 82 and 84 are so positioned that the piston 68 is always located between them under all conditions of operation.

A pair of L-shaped brackets 86 and 88 are clamped rigidly to the upper section support bars 46 and 48 to provide a support for a cross bar member 90. One leg of each of the L-shaped brackets is provided with a circular opening 92 and 94, respectively, into which are fitted sleeve bearings 96 and 98, so that the cross bar 90 can rotate freely about its axis. Depending bars 102 and 104 are rigidly secured near the ends of the cross bar 90 by means of bolts 106. Pivotedly secured to the lower ends of the depending bars 102 and 104 are respective link members 108 and 110, the opposite ends of the link members being pivotally connected to the upper section carriage members 50 and 52 respectively by means of bolts 112 and 114.

In the operation of this web tension control device, the vertical frames 18 and 20 of the first or lower section are urged to the right (Fig. 1) by the adjustable spring 34, which force is opposed by the tensional force in the V-belt 32 which drives the roller 12. In addition, the vertical carriage frames 18 and 20 are urged by the web 10 in the leftward direction to a degree depending on whether the web is moving momentarily too fast or too slowly through the web tension mechanism. If, in operation, there is an increase in tension of the web 10 traveling through this device, the lower section vertical carriage frames 18 and 20 would be displaced to the left (Fig. 1). This motion displaces the connecting link 60 (which connects the upper and lower sections) and the air cylinder control rod 62 also to the left. This movement of the control rod exposes the valve port 82 (Fig. 4) thereby permitting pressure fluid to enter the cylinder 64. Since the piston 68 and piston rod 70 are held immovable by the clamping bar 72, the cylinder 64 itself will be forced to the left (Fig. 1). This motion to the left of the cylinder 64 will continue until a position is reached where the valve 78 covers the valve port 82 (Fig. 4). The cylinder 64 then comes to rest until the control rod 62 is moved again because of movement of the lower section vertical carriage frames 18 and 20. Since the cylinder 64 is bolted securely to the upper section carriage frame 50, any movement imparted to the cylinder causes movement also of the carriage frame 50. Thus the movement of the lower section to the left causes the cylinder 64 and upper section carriage frame 50 to move to the left an amount identical to the movement of the control rod 62. Hence, the idler roller 58 mounted in the upper section carriage members 50 and 52 is moved to the left an amount identical to the movement of lower section vertical carriage frames 18 and 20, preserving the web length constant and the section of web between rollers 16 and 58 vertical.

The above described arrangement and operation ensures that motion of the first or lower section carriage frames 18 and 20 will be followed accurately by upper section carriage frame 50. Therefore the first or lower section carriage frame and the second or upper section carriage frame always have the same relative position, thereby maintaining a substantially constant web length between the entering point R and the exit point S to affect the web tension at entering point R. The web tension of entering point R is held constant within certain predetermined limits by the action of this web tension control mechanism.

Although the invention has been described and illustrated as comprising an upper and lower section, it is ob-

vious that changes may be made in the relative locations of the two sections without departing from the spirit of the invention. Although a variable speed V-belt drive has been described for driving the feed roller in the first or lower section it is obvious that equally desirable results can be obtained by the use of sensitive hydraulic or electrically controlled drives. In addition, the lower or first section biasing spring 34 may be replaced by a piston and cylinder arrangement utilizing adjustable fluid pressure control, or other equivalents.

Figure 1 shows the device arranged for a web which enters at R and departs at S, travelling from left to right. It is obvious that the same device can be arranged with the web travelling in the opposite direction, or from S to R. In either case, the constant-tension section of the web will lie, in Figure 1, to the left of the device itself.

The invention has been described above in connection with a single preferred form given by way of illustration; however, the details of the equipment used in carrying out the teachings of the invention can readily be varied by those skilled in the art. All such changes and modifications falling within the true spirit and scope of the invention are intended to be covered herein, to the extent that they fall within the terms of the appended claims.

What is claimed is:

1. In a web tension control mechanism, the combination comprising a first section and a second section, said first section including at least a first rotatably and movably mounted roller around which the web is passed, said roller being so mounted as to move in a lateral direction an amount proportional to the tension of the web passing around said roller, said second section being spaced from said first section and including an idler roller around which the web is passed, servo mechanism actuated by the lateral movement of said first roller for moving said idler roller an equal amount in the same direction as said first roller, whereby the web length between said rollers remains substantially constant regardless of web tension, and means for regulating the web tension in one of said sections.

2. In a web tension control mechanism, the combination comprising a first section and a second section, said first section including a slidably mounted carriage carrying a driven roller around which the web is passed, said carriage being biased for movement in one direction and subject to movement in response to changes in web tension, said second section being spaced laterally of the web travel direction from said first section and including a slidably mounted carriage carrying an idler roller around which the web is passed, and power means controlled by the movement of said first carriage for moving said second carriage an equal amount and in the same direction as said first carriage whereby the web length between said rollers remains substantially constant regardless of web tension.

3. In a web tension control mechanism, the combination comprising a first section and a second section spaced therefrom, said first section including a slidably mounted carriage carrying rollers around which the web is wound in serpentine fashion, said carriage being biased in one direction and subject to movement in response to changes in web tension, said second section including a slidably mounted carriage carrying an idler roller around which the web is passed from said first section, control means linking said two sections, and power means actuated by said control means for moving said second carriage an equal amount and in the same direction as said first carriage whereby the web length between said sections remains substantially constant regardless of web tension.

4. The combination as set forth in claim 3, in which the power means to move the second carriage includes a fluid cylinder connected to said second carriage.

5. The combination as set forth in claim 3, in which

the two sections are spaced apart in two directions perpendicular to each other.

6. A web tension control mechanism comprising a first section and a second section vertically spaced therefrom, said first section including a slidably mounted carriage, a plurality of rollers carried by said carriage and around which the web is passed in serpentine fashion, means for biasing said carriage in a direction to oppose the web tension, said second section including a carriage slidably mounted for movement parallel to said first mentioned carriage, said second carriage having mounted thereon an idler roller around which the web is passed after leaving said first section, the web path between said carriages being perpendicular to the direction of carriage move-

ments, control means linking said two sections, power means connected to said second carriage and controlled by said control means to move said second carriage an amount equal to and in the same direction as said first carriage in response to changes in web tension, whereby the web length between said sections remains substantially constant regardless of changes in web tension, and a tension control connected to one of the rollers of said first section.

5 7. The combination as set forth in claim 6, in which the power means to move the second carriage includes a fluid pressure cylinder mounted upon said second men-
10 tioned carriage.
